UNITED STATES PATENT OFFICE.

FREDOLIEN J. OBERER, OF PORTLAND, OREGON, ASSIGNOR, BY DIRECT AND MESNE ASSIGNMENTS, TO IRONCLAD SILO COMPANY, OF PORTLAND, OREGON, A CORPORATION OF OREGON.

BAND FOR CIRCULAR CONTAINERS.

1,195,602.

Specification of Letters Patent. Patented Aug. 22, 1916.

Application filed February 14, 1914. Serial No. 818,807.

To all whom it may concern:

Be it known that I, FREDOLIEN J. OBERER, a citizen of the United States, and a resident of the city of Portland, county of Multnomah, State of Oregon, have invented a certain new and useful Improvement in Bands for Circular Containers, of which the following is a specification.

My invention relates to the hoops or bands 10 of circular containers built of staves, and especially relates to silos. Since the latter are built with a flat surface at the front side for the doors, and the bands must include flat bars at this part, it is found convenient to make the bands of rods bent 15 around the silo body and to secure the ends of the rods to said flat bars by means permitting the relative shortening and lengthening of the rod bands, so as to tighten and 20 loosen the same.

My invention has for its object the providing of improved simple, efficient and convenient connecting elements between the ends of said flat bars and said bands; also 25 to provide bands or hoops including straight and flat members for the front or the door side of the silo.

To this end my invention consists of a double flanged bar preferably made of two 30 angle bars, and swivel lugs pivotally secured between the flanges and at the ends of said bar so as to be rotatable on vertical axes. The swivel lugs are each made with a horizontally extending eye to receive one end 35 of a band. The extremities of the latter are threaded, and nuts are placed thereon for securing said ends against slipping out of the eyes of the lugs and also for relatively lengthening and shortening the band. The 40 threading of the extremities of the band and the nuts thereon, however, are to be understood as merely representing means for relatively shortening and lengthening the band. By making the lugs rotatable they better 45 accommodate the ends of the band, and facilitate the insertion of the ends of the band; for the eyes may be aligned with the band-ends to be inserted therein. This arrangement also permits the band to so adjust 50 itself as to properly encircle the circular stave body, and thus hold the staves firmly together.

In the accompanying drawings: Figure 1 shows portions of the stave body of the silo 55 adjacent the door, part of the frame of

which is shown; this view illustrates the general construction and operation of my improved bands; Fig. 2 is a top view of one of the swivel lugs included in my device; this view showing the related end of the band as inserted in said swivel lug and having a nut threaded on its extremity by the adjustment of which the band is relatively shortened and lengthened; and Fig. 3 is a sectional elevation of the right end of the 60 double flanged bar in which the swivel lugs are trunnioned and shows the details of construction preferably employed by me in carrying my invention into practice.

a represents portions of a silo body built 70 of staves and *b* portions of the door frame.

c is a spacing bar located between the door frame members *b b*. On the spacing bar are bolted by bolts *c'* two angle bars *d e*, the ends of which are secured to the door members *b b* by bolts *c''* as shown. The flanges, *d', e'*, of the angle bars are made with bearing holes near their ends to receive the trunnions *f'* of the swivel lugs *f*; the latter are castings each made with an eye *g*, extending 75 transversely therethrough.

h represents a band made in the form of a rod encircling the stave body. The ends *h'* of the rod *h* are threaded. Said ends are inserted through the eyes of the swivel lugs 80 *f* and after having been so inserted nuts *i* are placed on the threaded ends to prevent them from pulling out, and also to relatively shorten and lengthen the band, and thereby tighten and loosen the same. In 90 practice one end of the band *h* is first inserted in one of the swivel lugs *f*, and the other end of the band is then brought around the body of the silo and inserted in the swivel lug at the opposite end of the 95 bar *c*. The difficulty arose in the last mentioned act, in the devices heretofore employed. The eye through which the end of the band had to be brought could not be aligned properly so as to accommodate the insertion of said end; but by making the swivel lug rotatable on a vertical axis, it can be readily arranged so as to facilitate the insertion of the band end. Since the 100 bearing strain is in a direction longitudinal to the angle bars, *d, e*, there is no lateral strain on the angle bar members, to force them apart, and the swivel lugs cannot 105 become displaced or work themselves loose.

I claim:

110

1. A band or hoop comprising a double flanged bar consisting of two parallel members, the flanges being made with bearing holes at their ends, swivel lugs made with 5 trunnions bearing in the bearing holes of said flanges, said swivel lugs made with eyes, a band having its ends inserted through the eyes of said swivel lugs, and means for relatively shortening and lengthening the 10 band.
2. A band or hoop comprising a double flanged bar consisting of two parallel mem-

bers, the flanges being made with bearing holes at their ends, swivel lugs made with trunnions bearing in the bearing holes of 15 said flanges, said swivel lugs made with eyes, a band having its ends inserted through the eyes of said swivel lugs, and nuts threaded on the ends of said band.

FREDOLIEN J. OBERER.
